(57) **CLAIM**

What is claimed is the ornamental design for a drinking glass, as shown and described.

DESCRIPTION

FIG. 1 is a perspective view of a drinking glass, showing the new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines are included for the purpose of illustrating environment and form no part of the claimed design.
